The ornamental design for a intravenous pole with multiple electrical outlets, as shown and described.

DESCRIPTION

FIG. 1 is a front, perspective view of my intravenous pole with multiple electrical outlets showing my new design;

FIG. 2 is a right side elevational view thereof, the left side elevational view being a mirror image;

FIG. 3 is a top plan view thereof;

FIG. 4 is a rear elevational view thereof; and,

FIG. 5 is a bottom plan view thereof.
